Elijah Barnes North Brookfield Mass.

Setters Patent September 5. 1834.

8395X

The Schedule, referred to in these Setters Patent and making part of the same containing a description in the words of the said Elijah Barnes himself of his invention in preparing Cheese.

To all whom these Presents shall come, Be it known that I Elijah Barnes of North Brookfield in the County of Worcester and State of Massachusetts have invented a new and useful improvement in preparing Cheese and that the following is a full and exact description of the construction and operation of the said Machine as invented by me.

The use of my Cheese press may be made as the size of the Cheese may require. The utility of my Cheese press are considered superior to any other for many reasons. in the first place any wheel may be attached to one end of the second place it goes with one hand which moves with a guide by turning a handle or wheel required. a lever can be applied to the hub; and another advantage is the guide which the cheese passes through, and is connected with the head piece, with the pieces so that the cheese moves exactly true, the pivot that is bed in the end of the wheel which moves in a box that is bed in the head piece or press head press upon the cheese is another advantage by taking off the pivot is almost wholly one more advantage in my press. This if the cheese hoop is not very small it will admit of the head piece falling on the hoop if the cheese does not fit the hoop. Presses heretofore in use generally press upon the follower with a beam which causes considerable trouble in blocking up between the follower and the beam. The former press are considered press not by experienced dairy people, to those of the public or less because they are liable to break to hard at first and consequently force out the whole whey or goodness of the cheese.
